AND G. L. MORRIS, BOTH OF LOS ANGELES, CALIFORNIA

REED

PLASTER LATH.

1,115,593.

Specification of Letters Patent.

Patented Nov. 3, 1914.

Application filed October 28, 1913. Serial No. 797,756.

To all whom it may concern:

Be it known that I, JAMES P. SEXTON, a citizen of the United States, residing at Los Angeles, in the county of Los Angeles and 5 State of California, have invented a new and useful Plaster Lath, of which the following is a specification.

This invention relates to a plaster lath or mortar lath, which is adapted to be used 10 as a base or foundation for the plaster coat on walls and ceilings of buildings, and the main object of the present invention is to provide for securely locking or keying the plaster coat to the said base.

15 A further object of the invention is to provide a plaster lath base for the purpose stated, which will be unaffected by water, so that there is no swelling or warping of the base of any portion thereof by reason of the 20 dampness of the applied coat of plaster, and whereby any looseness or hollow spaces in the plaster coat is avoided.

Other objects of the invention will appear hereinafter.

25 The accompanying drawings illustrate embodiments of my invention, and referring thereto:

Figure 1 is a front elevation of a portion of the plaster lath showing at one part 30 thereof the plaster coat applied thereto. Fig. 2 is a section on line x^2-x^2 Fig. 1. Fig. 3 is a section on line x^3-x^8 Fig. 1. Fig. 4 is a section on line x^4-x^4 Fig. 1. Fig. 5 is a section on line x^5-x^5 Fig. 1. Fig. 6 is 35 a sectional view of a portion of the paper formed with reinforcing wire therein. Fig. 7 is a sectional view of the paper formed without the wire. Fig. 8 is a longitudinal section of the form of the invention in which 40 the key perforations are made in the sides instead of the bottom of the corrugations. Fig. 9 is a section on line x^9-x^9 Fig. 8. Fig. 10 is a vertical section of a form of the invention wherein the corrugations in the 45 paper form are bent over to secure a lateral interlock. Fig. 11 is a vertical section showing the application of the plaster keying buttons in coöperation with reinforcing wires. Fig. 12 is a vertical section showing 50 a double faced wall member adapted to receive a plaster coat on each side. Fig. 13 is a vertical section of another form of the invention. Fig. 14 is an elevation of a modified form of my invention. Fig. 15 is a sec-

tion on line $x^{17}-x^{17}$ Fig. 16. Fig. 16 is a 55 perspective of a form of the invention using buttons alone as keying means. Fig. 17 is a sectional view of another modification.

Referring to Figs. 1 to 7, the plaster lath comprises a form sheet or member 1 of paper 60 or other suitable material, a body or base 2 of plaster or mortar in adherent contact with said paper and forming a backing therefor, and keying means in connection with said form sheet and base for insuring 65 the retention of the plaster coat on the outside of the form. In order to facilitate the formation of the keying means and to provide a more effective contact for the applied plaster coat, I prefer to corrugate the form 70 member 1 as shown at 3, and at suitable points therein, for example, at the bottom of the grooves or depressions of said corrugations, said form member is perforated as shown at 4, so that when the plaster or mortar base 2 is applied to said form member, it 75 penetrates through said perforations forming buttons or heads 5, which flare outwardly from said perforations and form effective keys for retention of the plaster coat 80 indicated at 6, both by reason of the adaptability of the plaster surface of said buttons for adhering to the plaster coat, and of the dove-tailed shape of the spaces 7 between said buttons. The projection of these keys 85 over the plaster base, by reason of their enlargement outside of the form sheet, also serves to lock the base to the form sheet. In order to increase the keying action, and to give the effect of "furring," I may provide 90 keying members consisting of wires or cords 10, extending transversely through the corrugations 3 at suitable intervals, for example, through alternating rows of buttons 5, so that certain of said buttons embed or 95 inclose said members 10, while the other buttons do not contain any members 10. I prefer to arrange the buttons in successive corrugations in staggered relation, as shown in Fig. 1, thus providing a close and uniform 100 distribution of the buttons without causing the buttons to be spaced too closely either transversely or laterally. With this staggered relation of the buttons the reinforcing members 10 are left exposed at certain 105 portions as shown at 10' where they cross the grooves of the corrugations. It will be understood that the term "wires" as herein

used includes cords or other equivalents therefor. The above described plaster lath is made by bending the form member 1 into corrugated shape, the form member being preferably water proof, and the base 2 of plaster, mortar or other cementitious or plastic material is then applied to the back of said member 1, and squeezed through the perforations to form the buttons 5. A back 13 facing 12 of paper or other suitable material may then be applied to the plaster or mortar base before the plaster or mortar has become set. The ribs of the corrugations 3 project as high or higher than the plaster buttons 5 and protect said buttons, so that the lathing may be shipped or stored without breaking off the buttons. The structure formed as above described is sufficiently rigid and strong to serve all the purposes of a lathing 15 material, and forms an effective lathing and base for the plaster coat. The plaster lath formed as above described is secured in position on a wall of the building in any suitable manner, for example, by nails driven 20 through the same, and the plaster coat indicated at 6 is applied to the outer face thereof, said plaster coat interlocking with the keying buttons 5, and the keying wires or cords 10, so as to be secured or retained on 25 the base.

The water proofing of form member 1 has the advantage that when the plaster is applied to the plaster lath, as above described, the form member 1 does not absorb water 35 and become swelled or loosened and therefore retains its shape, so that when the plaster coat dries, there are no gaps or vacancies left between the plaster coat and the base. In applying the plaster coat to plastered boards having a paper facing, the objection has arisen that the paper is swelled and warped by the moisture of the plaster coating, and loosened by the weight of the plaster and when the parts become dry the 40 paper shrinks away from the plaster coat leaving vacancies or hollow spaces back of the plaster coating with a result that the plaster coating is liable to become detached. By water proofing the form member for the 45 base, this objection is obviated, and the parts retain their shape throughout the operation. In some cases, however, the supporting action of the buttons and the corrugations is sufficient to prevent sagging of the paper 50 form sheet, even without waterproofing and the waterproofing may then be dispensed with. The cords or wires may be omitted as in the form shown in Fig. 16, the construction being otherwise as above described. 55 In place of making the perforations in the bottom of the groove in the base, such perforations may, as shown in Figs. 8 and 9, be made in the sides of the corrugations or 60 grooves 15, of the form member 16, so that 65 the mortar or plaster backing or base 17 ap-

plied to the back of the form member 16 extrudes through these perforations 14 forming bridges 18, which serve the purpose of keying buttons and permit the plaster coating 19 to flow beneath the same as shown at 70 19' to give a more effective keying action.

As shown in Fig. 10, the corrugations 20 of the form member 21 may be bent over so as to overhang the buttons 22 formed by the plaster being forced from the back or base 23 through perforations 34 in the form member, so that said buttons are engaged and retained in such overhanging portions of the corrugations.

As shown in Fig. 11, the form sheet may 80 be provided with such intermediate corrugations indicated at 30 which may be perforated as shown at 31 so as to allow plaster to pass from the back 32 through form 33 and form buttons 34 embodying, or embedding the wire 35 which passes through the main corrugations 36.

By placing two of the above described plaster laths back to back or by doubling over the plaster lathing so as to form a double face member, as shown in Fig. 12, the invention may be used for forming walls, capable of being used for partitions and the like, and adapted to receive plaster coating for each side.

By rounding the corrugations of the form member as indicated at 35 in Fig. 13, the plaster lathing constructed according to my invention is adapted to receive any suitable metallic lathing or wire netting, which can 100 be nailed to the rounded outer edges of the corrugations.

The form member for the plaster lathing may be made flat, as shown in Figs. 14 and 15, and provided with perforations 38, 105 through which the plaster back 29 extends to form keys 40 adapted to contact with and form an adhering surface for the plaster coating.

Instead of corrugating the form sheet, 110 the depressions may be formed as counter-sinks therein, as shown at 45 in Fig. 17, the plaster base 46 extruding through a perforation 47 at the bottom of each counter-sink or depression to form a button 48 which is housed or protected by the counter-sink.

The corrugations above described also form depressions for housing and protecting the keys, said keys extending from the plaster base through the perforations into the depressions formed by said corrugations. In such a construction in which the keys project from the form sheet, but are located within the depressions in the form sheet, the keys are protected from damage during 115 storage and shipment and the plaster laths can be stacked or piled upon one another without liability of breaking or injuring the keys. This also provides a flat surface for 120 applying and smoothing plaster over the 125 130

lath, the tops of the keys being substantially flush with the elevated parts of the form sheet between the depressions.

What I claim is:

5. 1. A plaster lath comprising a perforated form member and a cementitious base on the back of said form member, extending through the perforations in the form member and projecting from the form member to 10 form keys.
2. A plaster lath comprising a form sheet having depressions and provided with perforations in said depressions, a cementitious base on the back of said form sheet, and cementitious keys extending from said base 15 forwardly through said perforations and projecting from said form sheet into said depressions.
3. A plaster lath comprising a form sheet 20 having depressions and provided with perforations in said depressions, a cementitious base on the back of said form sheet, and cementitious keys extending from said base forwardly through said perforations and 25 projecting from said form sheet into said depressions, said keys being arranged in rows and in staggered relation in successive rows.
4. A plaster lath comprising a form sheet 30 having depressions and provided with perforations in said depressions, a cementitious base on the back of said form sheet, and cementitious keys extending from said base through said perforations and flaring outwardly so as to project over said form sheet 35 to lock the cementitious base to the form sheet and serve as keys for retaining an

applied coating on the face of the plaster laths.

5. Plaster lath comprising a form sheet 40 having depressions and provided with perforations in said depressions, a cementitious base on the back of said form sheet, and cementitious keys extending from said base through said perforations and flaring outwardly so as to project over said form sheet 45 to lock the cementitious base to the form sheet and serve as keys for retaining an applied coating on the face of the plaster laths, the outer end surface of said keys being substantially flush with the outer surface 50 of the said form sheet.

6. As a new article of manufacture, plaster lath comprising a body having depressions on that side which is to receive an applied coating, the body being provided with buttons projecting from that side of the body which is to receive an applied coating, said buttons extending into said depressions, the outer ends of said buttons being substantially flush with the elevated portions of the body, said depressions forming cavities which are filled with the coating when applied, said buttons being surrounded by and embedded in the said coating when the latter 60 is applied, and keying the said coating to the body.

In testimony whereof, I have hereunto set my hand at Los Angeles, California, this 17th day of October, 1913.

JAMES P. SEXTON.
